UNITED STATES PATENT OFFICE.

EDWARD C. BEALS, OF SAN MATEO, CALIFORNIA.

DISAPPEARING WINDOW.

1,282,367.

Specification of Letters Patent. Patented Oct. 22, 1918.

Application filed January 5, 1917. Serial No. 140,767.

To all whom it may concern:

Be it known that I, EDWARD C. BEALS, a citizen of the United States, residing at San Mateo, in the county San Mateo and State of California, have invented certain new and useful Improvements in Disappearing Windows, of which the following is a specification.

This invention relates to disappearing windows of the general type in which the sash is adapted to be lowered into a pocket. One of the objects of my invention is to provide a movable stool which normally covers the top of the pocket and forms a part of the sill construction to support the sash when in raised position and which may be readily shifted from the inside of the room when it is desired to lower the window into the pocket.

In the accompanying drawings, Figure 1 is a vertical section of a window construction embodying my invention; Fig. 2 is a plan view of the link guides for the movable stool; Figs. 3 and 4 are detail views of parts of said guides; Fig. 5 is a vertical section of a modified form of my invention; Fig. 6 is a cross-section through one side of the window frame and sash but showing my separable sash; Fig. 7 is a plan view of one of the lateral guide plates for the movable stool; and Fig. 8 shows detail views of the guide pins carried by the movable stool.

The window frame may be of the usual construction and is provided with an outer sill 1, having an upstanding flange 3 at its inner side to coöperate with the depending flange 5 at the front edge of the movable stool 6, to form a weather-tight joint.

The stool 6 is preferably formed with a raised portion 6^a, providing a ledge 6^b extending along the inner edge of the base of the sash 8 and forming a weather-tight joint therewith. The front of the stool is provided with raised portions or projections 7, adapted to engage the outer side of the sash, forming a stop to prevent outward movement and coöperating with the ledge 6^b to position and securely hold the sash. The top of the sash is held between the front and rear stops 18 and 19, the head-jamb 20 being recessed at 21 to permit the sash to be raised when it is desired to slide the stool 6.

In order that the stool 6 may automatically move upwardly and ride over the

ledge 5 and the forward edge of the inner sill 10, as the operator pulls inwardly upon the knob or knobs 12, I provide toggle links 15 at each end of the stool to serve as guides during the movement from the full line position to the dotted line position shown in Fig. 1. The end plates 16^a, 16^b, to which the links are pivotally connected are secured respectively to the bottom of the stool and to a window frame member 17. I preferably bevel the forward edge of the sill 10 and correspondingly incline or bevel the inner edge of the stool 6 as shown, these inclined edges serving as rear guides which coöperate with the toggle links in lifting the stool as it is drawn rearwardly.

In the modification shown in Fig. 5, in lieu of the toggle links previously described, I provide guide plates 25, at either side of the window frame which are provided with angular slots 26, to receive the guide-lugs 27, carried by angle-plates 28 fastened to each side of the stool 6. When the stool 6 is lifted and moved rearwardly by the knob 12, the lugs 27 sliding in the slots 26 cause the front portion of the stool to move over the ledge 3, and to ride over the top of the sill 10.

The sash may be balanced in the usual manner by means of a sash cord 30 secured to the sash and passing over pulleys 31 secured in the pulley stile 32 adjacent the top of the window frame, and secured to weights 34, as I have illustrated in Fig. 6.

To facilitate the washing of the windows in the upper stories, I make the sash in two parts 2^a, 2^b, which are fastened together by means of two-part bolts. The outer bolt part 35 is tubular with internal threads and preferably squared on its outer side so that it may be driven tightly into a hole in the sash and will remain without turning. The inner solid bolt member 36 is exteriorly threaded to engage the interior threads of the member 35. By removing the bolt members 35, the inner sash 2^b carrying the glass, may be removed from the sash part 2^a.

When it is desired to lower the sash into pocket 40, the sash is lifted slightly into the recess 21 in the head jamb, the stool 6 is then slid back into dotted line position by means of the knob 12, and after the sash has been dropped into the pocket 40, the stool is moved back into normal position over the pocket. By reason of the action of the toggle links 15 or the guide plates

25, coöperating with the beveled edges of the stool and sill, the stool 6 is maintained in a substantially horizontal position during its entire movement and inasmuch as 5 the sash must be lifted only enough to permit the stool to clear the ledge 3, a slight elevation of the window sash is sufficient.

I have described in detail the construction 10 illustrated in the accompanying drawings for the purpose of disclosing embodiments of my invention, but it is evident that various modifications may be made within the scope of my claims and without departing from the spirit of my invention.

15 I claim:—

1. A disappearing window construction, comprising a window frame including an upper window opening and a window receiving pocket below, a horizontally movable stool mounted in the frame and normally covering the pocket and supporting the sash when in the window opening, and guiding means operating to raise the entire stool as it is moved rearwardly from its 25 position over the pocket.

2. A disappearing window construction, comprising a window frame including an upper window opening and a window receiving pocket below, a horizontally movable stool mounted in the frame and normally covering the pocket and supporting

the sash when in the window opening, and guiding means connecting the frame and the stool and which lifts the stool obliquely upward and then rearward when the stool is 35 moved rearward from its position over the pocket.

3. In a disappearing window provided with a pocket below the window opening, a movable stool adapted to support the sash 40 in raised position and to cover the window pocket, and pivotal means connecting the stool and the window frame adapted to lift the stool obliquely upward and permit it to move horizontally as it is drawn rearward. 45

4. A disappearing window construction, comprising a window frame including an upper window opening, a window receiving pocket below, and a sill having a raised 50 portion at its rear edge, a stool adapted to cover said pocket and having a depending ledge at its forward edge adapted to extend over said raised sill portion, and means adapted to lift the stool over and above 55 said raised sill portion when the stool is moved rearwardly and to lower the stool thereover as it is moved forwardly.

In testimony whereof I affix my signature.

EDWARD C. BEALS.
